UNITED STATES PATENT OFFICE.

GREENLEAF WHITTIER PICKARD, OF NEWTON CENTER, MASSACHUSETTS, ASSIGNOR
TO WIRELESS SPECIALTY APPARATUS COMPANY, OF BOSTON, MASSACHUSETTS,
A CORPORATION OF NEW YORK.

CLOSED TUNED COIL OR LOOP AERIAL.

Original application filed June 30, 1921, Serial No. 481,498. Divided and this application filed October 17, 1923. Serial No. 669,011.

To all whom it may concern:

Be it known that I, GREENLEAF WHITTIER PICKARD, a citizen of the United States of America, and a resident of Newton Center, State of Massachusetts, have invented certain new and useful Closed Tuned Coil or Loop Aerials, the principles of which are set forth in the following specification and accompanying drawings, which disclose the 10 form of the invention which I now consider to be the best of the various forms in which the principles of the invention may be embodied.

This is a division of my application, Serial No. 481,498, filed June 30, 1921, and relates more particularly to the invention of Figs. 3-5 thereof which invention may be embodied to contain various features of the other figures.

20 This invention relates to closed tuned coil or loop aerials for receiving and transmitting in radio communication and of the type of receivers known as direction finders or radio compasses and of the type of transmitters for directional transmission. The present invention is an improvement over the invention disclosed in my Patent 876,996, granted January 21, 1908.

The advantages of closed tuned loop aerials of one or more turns, such as disclosed 30 in Patent 876,996 are now well known. Such aerials when used for receiving have sharply directional properties and are used extensively for direction finding, as on ships and air planes, that is, for determining the 35 location of a distant transmitter, and for the purpose of guiding and directing the ship or air plane. Such loops are also used for receiving signals and messages because, 40 by reason of their directional properties and sharp tuning, static and interference are in a large measure eliminated or reduced.

The theory of operation in receiving of 45 such a closed tuned circuit as disclosed in my patent above-mentioned and disclosed in this application in an improved form is briefly as follows: The electromagnetic waves set up by the distant transmitter cut the closed tuned loop or receiving aerial in 50 the same manner that the lines of force generated around a primary of a transformer

cut the turns of the transformer secondary, setting up currents in the secondary circuit. In like manner, the electromagnetic waves in cutting the loop aerial, which is tuned 55 to the frequency of the transmitted waves, set up oscillations in the aerial. The electromagnetic flux which cuts the closed tuned aerial increases with its enclosed area or turn area. A loop or closed aerial operating according to the above principle must 60 be positioned with its plane in line with the distant transmitter in order to receive maximum signal or energy. In a plane at right angles to the transmitter, the loop receives 65 no energy from the transmitter nor is it affected by it. The voltage induced by the above flux in a closed radio loop of the above character depends upon the enclosed area or number of turns. However, it has 70 been found that such a closed circuit has more sharply directional properties, and is more efficient if the resistance is a minimum. This means that the loop operates better without any resistance in series with it. 75 Even a coupling inductance as disclosed in Fig. 3 of the above-mentioned patent introduces a certain amount of resistance, and for this reason the loop is more efficient if it consists of one turn rather than a number 80 of turns, which increases the resistance of the loop. Furthermore, the conductor resistance of such a closed loop circuit should be as low as possible for optimum results in receiving or for direction finding. Finally, as the voltage generated in the loop circuit increases with the number of turns or inductance, while the current decreases in the same proportion, I have found it 85 advantageous to make the voltage low and the current high. A loop circuit closed through a condenser does not have all of its capacity localized in this condenser. By reason of the inevitable proximity of earth and other conducting objects, a certain amount of 90 electrostatic capacity results from the conductor or conductors of the loop to its surroundings. If, as in a multturn loop, the condenser is of small value (because of the large inductance of a multturn loop), this 100 external electrostatic field may be relatively large, and if the disposition of surround-

ing objects is not symmetrical, the directional properties of the loop are impaired. If the loop be made of minimum inductance, that is, a single turn, the capacity of the 5 condenser becomes large as compared with the external electrostatic field, and the disturbing effect of surrounding objects is minimized.

In using the radio compass or direction 10 finder, it is an advantage, however, to have the loop aerial receiving set of minimum volume and extension. This compactness is obtained in present-day radio compasses and direction finders by providing multiple 15 turns instead of a single turn, whereby electromotive forces developed in each turn by the cutting of the magnetic waves are added together to produce an increased E. M. F. in the loop for actuating the receiving apparatus or detector. Such a system, however, is 20 inefficient electrically, and it also is not possible to obtain sharply directional properties on account of the small capacity necessitated by the high inductance of the multturn loop, 25 as above explained. Also, the increased resistance due both to the increased length of wire necessary for the multiple turns, and the increased high frequency resistance caused by the adjacent turns is wasteful of 30 energy.

In such direction finders as are now in use, the energy or oscillations set up in the coil are detected by means of a detector circuit connected in shunt with the closed aerial and 35 in shunt with the condenser in series with the aerial in the manner disclosed in Figure 2 of the above patent or occasionally by way of an inductive coupling such as a transformer having an inductance coil in series 40 with the loop and inductance coils in series with the receiving circuit, as shown in Figure 3 of my patent. These two modes of connection, while completely operative, have involved certain disadvantages such as decreased 45 signal reception through high resistance and a certain loss in sharpness of directional characteristics by reason of the high loop inductance, as explained above, this latter disadvantage being quite serious when 50 the loop aerial is used as a direction finder or radio compass.

An object of the invention is to provide a loop aerial in which the efficiency and directional properties are increased.

Another object of the invention is to provide a loop aerial and detector circuit in which the electrical connection between the two obviates the use of long leads or resistance-introducing coupling coils such as have 60 heretofore been used.

Another object of the invention is to provide a closed loop aerial and receiving detecting circuit in which electrostatic troubles between the loop, surrounding objects and 65 the receiving circuit to the detriment of the

directional properties and efficiency of the loop are obviated.

Another object of the invention is to provide a compact, simple construction of few parts which may be easily handled and operated. 70

In the accompanying drawings, I have illustrated embodiments of my invention in which—

Figure 1 is an elevation with parts in section of one feature with which the invention of Figs. 3-5 may be embodied; 75

Fig. 2 is a sectional plan view on the line 2-2 of Fig. 1, looking in the direction of the arrows and on an enlarged scale; 80

Fig. 3 is an elevation of an embodiment of the invention;

Fig. 4 is a plan view thereof;

Fig. 5 is a detail sectional plan view on the line 5-5 of Fig. 3, looking in the direction 85 of the arrows;

Fig. 6 is a sectional elevation of another feature with which the invention of Figs. 3-5 may be embodied, and illustrated diagrammatically; and 90

Fig. 7 is an elevation, partly in section, of another feature with which the invention of Figs. 3-5 may be embodied and illustrated diagrammatically.

Referring to Figs. 1 and 2, I have illustrated a closed aerial circuit 1 which is completed through a static condenser system 2. This condenser system, which is in series with the closed loop, is made (because of the low inductance of the loop of the present invention) in two parts 2^a and 2^b in parallel with each other and both connected or connectable in series with the loop 1. The part 2^a comprises a number of condensers, preferably mica condensers, each having different capacities and one and all being capable of being connected in series with loop 1. The part 2^b is a variable condenser, and after the approximate resonant capacity value of the condensers 2^a is obtained, the final tuning adjustment may be secured by the variable condenser 2^b. 100

The condenser system 2 comprises a metal casing C, supporting the aerial 1, and provided at the bottom with a vertical tubular 115 extension 3, rotatably supported in frame 4, ball bearings 5 being provided for easy turning, whereby the entire apparatus, including the casing C, condensers 2 and the loop 1, may be rotated about a vertical 120 axis for the purpose of properly positioning the same with reference to the distant transmitter. The lower end of the tube or sleeve 3 is provided with an adjusting wheel or handle 6. The loop 1 is supported 125 on casing C and insulated therefrom by bushings 7 of any suitable insulating material having good dielectric properties such as bakelite dielecto or quartz, the bushings being arranged at diametrically opposite 130

posite points in casing 2. The free ends of the loop 1 are inserted within these bushings 7 and project inside of the casing C. One end of the loop is provided with a 5 metal segment 8 to which are electrically connected adjacent ends of the condensers 2^a and 2^b. Telescoping the tube 3 is a sleeve 9 provided at its lower end with an operating wheel or handle 10 and terminating 10 at its upper end within casing 2 in an insulating plate 11 of suitable insulating and dielectric properties. Secured to the upper surface of the insulating plate 11 is a metal plate or segment 12 adapted to 15 engage contact fingers 13 (Fig. 2) upon the condensers 2^a at the ends thereof remote from their points of connection to the segment 8. A contact finger 14 also engages the plate 12 and is electrically connected through conductor 15 within casing C to the opposite end of the loop, whereby the circuit 1 is closed through one or more of the condensers 2^a. Extending vertically 20 through the sleeve 9 is an actuating rod 16 provided at its lower end with an operating handle 17 for operating the variable condenser 2^b. The upper end 18 of the rod 16 has secured to it the relatively adjustable plates 19 of the variable condenser 2^b, 25 which are interposed between the relatively fixed plates 20 of the variable condenser. The plates 20 are electrically connected to segment 8, while the plates 19 are insulated from the rod 16 by suitable insulation 21. 30 The relatively movable plates 19 are electrically connected by a conductor 22 to conductor 15.

By the above construction, it will be seen that in tuning the closed loop 1; one or 35 more of the condensers 2^a may be successively thrown into series with the loop 1 by means of the actuating handle 10 for securing rough adjustment and tuning of the circuit 1 and the final tuning and adjustment 40 may be secured by rotating handle 17, thereby actuating and varying the variable condenser 2^b. By means of the handle 6, the entire apparatus may be properly positioned. A coil 23, which with aerial 1 as a whole 45 constitutes a transformer and which may comprise a number of turns depending on given conditions, is secured by means of an adjustable collar 24 to the tube 3, this collar being adjustably clamped to tube 3 50 by any suitable clamping means 25. By rotating the collar 24 around the sleeve 3 and thereby rotating coil 23, the inductive coupling between coil 23 and loop 1 may be 55 varied for optimum effect. The leads 26 from coil 23 are electrically connected to any suitable detecting or transmitting circuit, such as, for instance, an audion circuit, crystal detector circuit or any standard 60 transmitting circuit, whereby the oscillations set up in the loop 1 are inductively

transferred to transformer secondary 23 and detected or whereby the reverse occurs on transmitting.

The coil aerial 1 in the present invention consists preferably of a single turn of low 70 resistance conductor, or, if so desired, may consist of more than one turn. If the loop be made of a single turn conductor, the most efficient form for this conductor is a circle of thin-walled copper tubing, as in 75 Fig. 1, while for a loop of more than one turn a suitably stranded or braided cable should be used (Figs. 6 and 7) to keep the high frequency resistance low. In all cases, the loop should enclose sufficient area to 80 be operative under any given set of conditions. By way of example, only, such a ring or closed loop may have a diameter across the same of three feet, the diameter of the tubular part being about 2 inches, 85 and the thickness of walls about 1/32 of an inch. Such construction, when properly tuned by the condenser system 2, constitutes a closed tuned circuit enclosing an area which, when its plane is in line with 90 the distant transmitter receives maximum current, and when at right angles to the transmitter, has a null point. The copper tubing loop such as disclosed in Figs. 1 and 2 has minimum resistance, minimum 95 inductance, maximum current and maximum capacity.

A single turn loop such as disclosed in Figs. 1 and 2 provides a closed circuit having high current and comparatively low voltage. 100 This circuit 1 as a whole, by reason of the oscillations impressed upon it by the electromagnetic waves, acts in receiving as a primary of a transformer which is in inductive relation to the secondary of the transformer 105 23 secured to the tube 3 below it. This secondary 23 is connected up to any suitable receiving and detecting circuit as described above. The secondary 23 is adjustably secured to sleeve 3, and can be adjusted around 110 sleeve 3 as an axis to vary the coupling between it and coil 1. In the use of the apparatus, the coil 23 is adjusted until maximum response or optimum response or signal is obtained. Thereafter, by means of the 115 clamping screw 25, the coil 23 is fixed relatively to the loop 1, and the whole, both coil 23 and loop 1, may be rotated in accordance with direction-finding practice.

An advantage of the type of coupling between the closed aerial 1 and the coil 23 resides in the fact that the coils 1 and 23 may be physically separated sufficiently so that there will be no electrostatic coupling or capacity effect between them which impairs 120 the efficiency of the apparatus as a direction finder. The optimum coupling between a receiving aerial circuit and the detector or secondary circuit depends upon the resistance 125 or damping of these circuits, and where the 130

resistance, as in my invention herein, is very low, the optimum coupling is also very low, thereby permitting a considerable physical separation between the circuits, which in turn minimizes the electrostatic effect. In constructions now in use in which the receiving circuit is connected by means of an inductive coupling in series with the loop 1 or by leads such as above referred to, forming a detector shunt with the loop, the electrostatic effects are detrimental to the efficiency of the circuit, because of the close coupling necessitated by the relatively high circuit resistance.

As is well known, the coupling between two coils of a transformer can be adjusted either by increasing the parallel separation between the coils, or by moving the coils transversely to each other, or by rotating one coil around an axis, whereby the angular position between the coils is varied. When the planes are parallel, we have maximum mutual inductance, and when the planes are at right angles, no mutual inductance. However, there is always an optimum position or coupling between the coils which can be easily determined by the operator for obtaining the loudest signal. This optimum coupling under any condition can be obtained with the two coils 1 and 23 spaced sufficiently apart to avoid electrostatic coupling.

Such an arrangement as above described, in which the closed aerial 1 as a whole constitutes a primary of an oscillation transformer and the coil 23 constitutes the secondary of the transformer, materially lowers the losses in the complete apparatus and ensures better tuning and efficiency. The decreasing of the resistance and inductance in the coil 1 ensures increased current and obviates the necessity for a large number of turns in coil 1. The number of secondary turns of the transformer 23 is large compared to the number of turns of the closed aerial whereby the necessary voltage is developed for operating the detector. In other words, in receiving, the coil 1 and the secondary 23 constitute a step-up transformer. This being the case, there is no necessity for a large number of turns in the loop 1 to generate the necessary voltage to operate the detector, this increased voltage being secured in the secondary 23 by the present invention.

An advantage of the construction shown in Figs. 1 and 2 is that the receiving circuit is of very low resistance because no coupling coil is used, nor are there any long leads. This permits the use of a single turn receiving coil, hence giving maximum efficiency. Again, the directional properties of the system are extremely sharp, because the closed loop circuit 1 has no long leads or connections to any more or less grounded circuit, as is the case in the ordinary modes of communication. Furthermore, the system is ex-

tremely simple because it is not necessary, as in the case of inductive couplings, to insert an inductance in series with the loop, nor is it necessary to provide long leads to the detector circuit.

As illustrated in Fig. 1, both the closed aerial or primary and the secondary coil 23 are mounted on the same frame, and if the apparatus is used on a single wave-length, the coupling may be made non-adjustable and fixed by the constructor at the best value. Of course, if used on wide wavelength ranges, the coupling between the coils 1 and 23 should be made variable in any suitable manner such as those enumerated above.

In Figs. 3, 4 and 5, I have illustrated a modified embodiment of the invention in which the number of movable and adjustable parts is reduced to a minimum and which is especially adapted for larger aerials which cannot be conveniently rotated. In this form, I have illustrated a closed loop or circuit 30 having in series therewith an adjustable tuning condenser 31 and a second closed loop or circuit 32 having in series therewith an adjustable tuning condenser 33. These two loops 30 and 32 may be secured in fixed position to any suitable insulating support 34 and are arranged in intersecting planes at right angles to each other as illustrated, the loops being substantially circular and of the same size, having similar electrical characteristics, insulated from each other, and arranged symmetrically relative to each other. The closed aerials 30 and 32 may comprise any suitable conductive material or any number of turns, but, for purposes of illustration, I have shown the same as being composed of my tubular constructions such as disclosed in Fig. 1. Extending vertically along the line of intersection of the two loops 30 and 32 is a rod 35, journaled at 36 in the support 34 and having a wheel or handle 37 at its lower end. Secured to rod 35 at its upper end is a coil 38 comprising any suitable or sufficient number of turns for the purposes of this invention. This coil 38 is arranged with its axis on a line coinciding with the line of intersection of the planes of the two loops 30 and 32 and is arranged centrally and symmetrically of the two loops. Leads 39 from the coil 38 may be connected to any suitable receiving or detector circuit as above described or a transmitting circuit. Secured to rod 35 above the handle 37 is a pointer 40 adapted to play over a dial 41, whereby the direction may be determined.

Electrical oscillations set up from a transmitter at any point in a horizontal plane will affect the two aerials 30 and 32 differentially depending upon the location of the transmitter. However, when the coil 38 is rotated, its position, when maximum re-

sponse is noted in the receiver or telephone, indicates the position of the distant transmitter, that is to say, when the maximum response is observed, the plane of the coil 38 will be in line with the distant transmitter. By the above construction, I am enabled to obtain direction without necessitating the rotation of the aerial or aerials.

At the same time, the necessity for varying 10 the inductive coupling between the loop and the coil and at the same time rotating both the loop aerial and secondary coil is obviated. The principle of the invention disclosed in Figs. 3 to 5 is the same as that disclosed in Fig. 1, that is to say, the aerials 30 and 32 as a whole upon receiving constitute the primary of a transformer, while the coil 38 constitutes the secondary of said transformer.

20 In Fig. 6, I have illustrated another embodiment of the invention comprising a closed aerial or loop 45, which may consist of several turns of stranded wire wound upon a suitable insulating frame 46 and in series with which is an adjustable tuning condenser 47. Located within loop 45 is a secondary coil 49 consisting of suitable number of turns of wire, preferably exceeding the number of turns in aerial 45, being 30 the equivalent of the secondary 23 illustrated in Fig. 1. However, in the present embodiment of the invention, the secondary 49 is illustrated centrally within the coil 45 and parallel with the turns thereof, which is 35 the position for maximum magnetic coupling. The secondary 49 may be adjusted for optimum coupling by rotating it around a vertical axis. The coil 49 may be connected through leads 50 to any desired form 40 of detector or secondary circuit. The aerial 45 with coil 49 constitutes a transformer functioning according to the principles of the invention described above.

45 In Fig. 7, I have illustrated a form of my invention slightly modified from that of Fig. 6, which comprises the closed tuned primary or loop aerial 51 comprising several turns tuned by a variable condenser 52 in series with it. Coupled with this loop 50 aerial is a secondary coil 53 of a sufficient number of turns. Any desired variation of coupling may be obtained by either moving the coil 53 axially away or towards the coil 51, or, as indicated by the double-headed 55 vertical arrow, coil 53 may be either moved laterally across the face of coil 51 or rotated around an axis parallel with the double-headed arrow, to vary the coupling.

60 The secondary circuit of Fig. 7 including coil 53 is tuned by a variable condenser 54, and the radio frequency amplifier 55 is connected between this secondary circuit and the indicator 56. In the form of Fig. 7, the diameter of the secondary 53 approximates or is of the order of magnitude of

that of the coil aerial 51, and such secondary 70 53, inasmuch as it is tuned to the frequency of the primary 51, acts as a closed tuned coil aerial to a certain extent, the current set up in coil 53 by the transmitted electromagnetic waves being added in quadrature to the currents transferred by induction from aerial 51 to coil 53.

The main features of the above-described 75 construction reside in the fact that the inductance and resistance of the closed aerial circuit is reduced to a minimum by reason of the omission of conductive leads and inductances inserted in series or in shunt in the circuit. The secondary coil with which 80 the primary or closed loop aerial co-operates as a whole is sufficiently spaced to prevent electrostatic couplings, but at the same time is so adjustably coupled to the closed aerial 85 as to receive maximum or optimum signal. This arrangement increases the sharpness of directivity by an appreciable amount. By the above construction, increased current is secured in the coil aerial, which current is transferred directly from the coil aerial 90 to a secondary of increased number of turns, whereby the required E. M. F. is generated in the secondary.

In short, my invention comprises a closed 95 aerial circuit, coupled inductively to a coil of a detecting or transmitting circuit, the two constituting the primary and secondary of an oscillation transformer.

A form of the present invention which I 100 have used consisted of 33 turns of $\frac{3}{8}$ inch Belden high frequency cable wound as a single layer solenoid on a square frame 44 inches on a side. This loop aerial with its associated tuning condenser, and when coupled to a detector circuit for maximum 105 signal, had the extremely low resistance of 1.2 ohms at a wave length of 12,500 meters. Good signals were received from European 110 stations, and, owing to the low resistance of the loop aerial, very sharp tuning was possible.

It is to be understood that the invention is not limited to the embodiments and features specifically shown and described herein, but that such embodiments and features are subject to changes and modifications 115 without any departure from the spirit of the invention.

I claim:—

1. Radio directional-loop aerial receiving 120 apparatus comprising two loop aerials operatively and permissively fixed in vertical planes at substantially right angles to and intersecting one another, said aerials thereby permitting production by transmitted waves, of a magnetic field the direction of which coincides with that of such waves; and a rotatable pick-up coil located in said magnetic field, acting as a secondary to 125 said loop aerials as a whole as a primary, 130

and affected by said field save when in a position at right angles to the source of such waves, whereby the position of the pick-up coil determines the direction of said 5 source of waves.

2. Radio directional-loop aerial receiving apparatus comprising two loop aerials of substantially the same enclosed area and permissively operatively fixed in vertical 10 planes at substantially right angles to and centrally intersecting one another, said aerials thereby jointly permitting the production, by transmitted waves, of a magnetic field the direction of which coincides 15 with that of such waves; and a rotatable pick-up coil located on the line thru the central intersection of said loop aerials and acting as a secondary to said loop aerials as a whole as a primary, whereby the position 20 of the pick-up coil determines the direction of the distant source of such waves.

3. Radio directional-loop aerial receiving apparatus comprising two loop aerials each of substantially the same enclosed area and each consisting of a single turn of metal tubing of low resistance, said two aerials being permissively operatively fixed in vertical planes at substantially right angles to and centrally intersecting one another, said aerials thereby jointly permitting the production, by transmitted waves, of a magnetic field within them generally on the line of their intersection, the direction of which field is that of such waves; and a rotatable pick-up coil located centrally within said two aerials and having relatively small area and consequently low electrostatic capacity with respect to said aerials and consequently only slight disturbing effect on the aerials, said pick-up coil acting as a secondary to said loop aerials as a whole as a primary. 25 30 35 40

GREENLEAF WHITTIER PICKARD.
